UNITED STATES PATENT OFFICE.

SWAN NELSON, OF WINNIFRED, ALBERTA, CANADA

PUMP.

1,328,010.

Specification of Letters Patent. Patented Jan. 13, 1920.

Application filed August 26, 1918. Serial No. 251 574

To all whom it may concern:

Be it known that I, SWAN NELSON, citizen of Canada, residing at Winnifred, in the Province of Alberta, Canada, have invented 5 certain new and useful Improvements in Pumps, of which the following is a specification, reference being had to the accompanying drawings.

This invention relates to certain improvements in pumps, and has relation more particularly to a device of this general character of a rotary type and it is an object of the invention to provide a pump having novel and improved means whereby the same may be operated with convenience and facility and whereby a continuous stream of water may be elevated and discharged upon operation of the rotor.

It is also an object of the invention to provide a novel and improved device of this general character including a casing adapted to be submerged and in which the rotor is positioned and wherein the side walls of the casing below the rotor are provided with induction openings.

20 induction openings.

A further object of the invention is to provide a novel and improved device of this general character wherein the casing in which the rotor is positioned is provided 30 with means whereby the fluid entering within the casing is held against circular or rotary movement within the casing under the influence of the rotor and whereby the lifting of the fluid is materially facilitated.

35 An additional object of the invention is to provide a novel and improved device of this general character including a casing adapted for submergence and provided with induction openings and wherein means are
40 provided to prevent entrance of sand, gravel or the like into the casing through the induction openings.

The invention consists in the details of construction and in the combination and arrangement of the several parts of my improved pumps whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood I will now proceed to

describe the same with reference to the accompanying drawings, wherein:

Figure 1 is a longitudinal sectional view taken through a pump constructed in accordance with an embodiment of my invention, certain of the parts being shown in elevation: 60

Fig. 2 is an enlarged view in top plan of the rotor as herein embodied, the coaxial shaft being shown in section:

Fig. 3 is a cross sectional view taken through the rotor as illustrated in Fig. 2, the coacting shaft being shown in elevation and in fragment; and

Fig. 4 is a horizontal sectional view taken through the casing at a point below the 70 rotor.

As disclosed in the accompanying drawings 1 denotes a head adapted to be suitably supported above or over the top of the well and extending upwardly from said head is a housing 2 preferably in the form of a truncated cone. At diametrically disposed points the upper end portion of the housing 2 is cut away as indicated at 3 so that no obstruction will be offered to the driving gear 4 which partially extends within the housing 2. The upper marginal portions of the housing 1 between the openings 3 and at opposite sides thereof have secured thereto the plates 5. Fixed or otherwise supported by the plates 5 are the bearings 6 with which the shaft 7 is rotatably engaged. The gear 4 is fixed to this shaft 7. One end portion of the shaft 7 is in line with the

tion of the shaft 7 extends beyond the housing 2 and fixed to the extended portion of the shaft is the pulley 8 which may be employed, should it be desired to rotate the shaft by power. The pulley 8 also serves as a balance wheel when the shaft 7 is rotated manually through the medium of a crank 9 or the like. As herein disclosed the inner end portion of the crank is fixed to the shaft 7 outwardly of the pulley 8 and an intermediate portion of the crank is secured to the peripheral portion of the pulley by a pin 10 or its equivalent. 90 95 100

The housing 2 below the cut away portion or recesses 3 is intersected by a substantially horizontally disposed plate or partition 11. The plate 11 at its axial center 105 has disposed therethrough a sleeve 12 extending above and below the plate or partition 11. This sleeve serves as a bearing or

support for the upper end portion of the shaft 14, as will be hereinafter more particularly referred to. Fixed to the shaft 14 at its upper end portion is a pinion 15 meshing with the driving gear 4 hereinbefore referred to whereby the shaft 14 is rotated in unison with the shaft 7. The shaft 14 below the pinion 15 is provided with an outstanding annular flange 16 contacting 10 with the upper end of the sleeve 12 whereby an effective support for the upper end portion of the shaft 14 is obtained. The flange 16 is provided with an oil opening 17 discharging between the periphery of the shaft 14 and the sleeve 12, so that the mounting of 15 the upper end portion of the shaft may be readily lubricated. Extending within the housing 3 above but in close proximity to the plate or partition 11 is an oiling vent or tube 18 having its inner end portion continued at its bottom by an extension trough 20 terminating above and substantially in contact with the flange 16 so that the oil delivered into the tube 18 through the outer 25 end thereof will be received upon the flange 16 and passed downwardly through the oil openings 17 for a purpose which is believed to be clearly apparent to those skilled in the art to which my present invention appertains.

30 Suitably secured at its upper end portion to the under face of the plate or partition 11 and concentric to the depending or lower end portion of the sleeve 12 is a tube or pipe 19 of a length required by the necessity of practice, or of a length to extend below the water level within a well or other source of liquid supply. Extending laterally from the tube or pipe 19 within the housing 3 and 35 disposed on a downward incline is a discharging spout 20. The spout 20 terminates exteriorly of the housing 3 and coacting with the outer or discharging end of the spout 20 is a flat valve or gate 21 which 40 normally overlies and closes the discharge end of the spout 20 so that the ingress therein of foreign matter is substantially eliminated. The flat valve or gate assumes its 45 normal or closed position by gravity but is readily raised or moved into open position 50 under the influence of the stream discharging through the spout 20.

55 C denotes a cylindrical casing having its upper portion 22 preferably in the form of a truncated cone and in communication with said upper portion or top at its axial center is the lower end portion of the tube or pipe 19. The tube or pipe 19 and the upper portion or top 22 of the casing C are suitably secured or anchored one to the other.

60 The bottom 23 of the casing C at its axial center is provided with upstanding hollow sleeve 24 in which extends the lower end portion of the shaft 14 and the bottom end of 65 said shaft contacts with an antifriction

member 25, preferably spherical, and which is positioned within the sleeve 24 and resting directly upon the bottom 23. As is clearly disclosed in the accompanying drawings the shaft 24 extends axially of the tube 70 or pipe 19 and casing C. At predetermined points longitudinally thereof, the tube or pipe 19 is intersected by the spider 26 or the like and which serves as an additional support for the shaft 14 and particularly to 75 maintain the same in proper alignment.

Fixed to the shaft 14 and at a distance above the bottom 23 of the casing C is a rotor R of a radius to substantially entirely intersect the casing C. The rotor R is substantially horizontally disposed and includes a hub plate 27 having its peripheral portion defined by a depending annular flange 28. Extending outwardly from the hub disk 27 and the flange 28 are the blades 29 having 85 their outer edges or extremities suitably engaged with their inner walls of an annular member 30. The hand or pitch of the blades 29 is such to cause water or other liquid entering within the casing C to be 90 lifted or elevated through the tube or pipe 19 and discharged through the spout 20. It will also be understood that the size of the stream discharged will depend upon the rate or speed of rotation of the rotor R.

95 The side wall of the casing C below the rotor R is provided with a plurality of entrance or induction openings 31, equidistantly spaced and preferably four in number. As herein disclosed the openings 31 are 100 rectangular in form and the corresponding vertical margin of each of the openings 31 is defined by an inwardly directed and substantially radially disposed plate or baffle 32 bridging the space between the side walls 105 of the casing and the sleeve 24. These plates or baffles 32 serve to hold the liquid entering the casing 3 against rotary or circular movement so that the functioning of the rotor R is materially facilitated.

110 In practice the casing C is entirely submerged and is generally positioned in close proximity to the well bottom or other source of water supply and for this reason it is essential that effective means be employed to 115 prevent ingress within the casing C of sand, gravel, or the like. For this reason I employ in connection with each of the openings 31 a shield S which is substantially U-shaped in cross section and decreasing 120 in depth throughout its entire length and from the top thereof. The shield S is of a length in excess of the height of the opening 31 with which it coacts and is also of a greater width. The side marginal portions 125 of the shield S are provided with the outstanding marginal flanges 33 which contact throughout their length with the outer face of the side walls of the casing C and are also engaged within the holding clips 130

carried by the casing C. The lower marginal portion of the shield S also contacts with the outer face of the side wall of the casing C. The lower marginal portion of the shield S is also engaged with a clip 35 which further assists in maintaining the shield S in operative position.

In view of the foregoing and as illustrated in the accompanying drawings it is to be noted that the upper end portion of each of the shields S is open so that the liquid before entering within the casing C through the openings 31, must pass downwardly of the shield and by which arrangement the possibility of sand, gravel, or the like entering within the casing C is substantially entirely eliminated.

Inclosing the portions of the driving gear 4 is a gear casing 36 of any desired configuration and which is suitably anchored or secured to the upper end portion of the housing 3.

From the foregoing description, it is thought to be obvious that a pump constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A pump of the class described, com-

prising a vertically disposed tube, supporting means therefor, coating with the upper portion of the tube, the opposite ends of the tube being closed, the lower end portion of the tube being provided in its side walls with circumferentially spaced openings, and a shield overlying each of said openings, said shield having its lower and side marginal portions in contact with the casing below and at opposite sides of the entrance opening, the upper marginal portion of the shield terminating above the opening, said shield being inwardly supported toward the tube from its upper edge to its lower edge and a water lifting means arranged within the tube above but in close proximity to the openings, the upper portion of the tube being provided with a discharge opening.

2. A pump of the class described comprising a vertically disposed tube having its lower end closed, means for supporting the tube in working position, the lower end portion of the tube being provided with an entrance opening in its side wall, a shield overlying said opening and having its bottom and side margins in contact with the tube, said shield having its upper margin above the opening, said shield being inwardly inclined from its upper margins to its lower margins, and lifting means arranged within the tube above but in close proximity to the entrance opening.

In testimony whereof I hereunto affix my signature in the presence of two witnesses.

SWAN NELSON.

Witnesses:

ERNEST A. HINCK,
PERRY WOLFORD.
